UNITED STATES PATENT OFFICE

WILLIS O. PROUTY, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A THERAPEUTIC LIGHT STANDARD

Application filed February 19, 1932. Serial No. 42,935. Term of patent 14 years.

To all whom it may concern:

Be it known that I, WILLIS O. PROUTY, a citizen of the United States, and a resident of the city of Hermosa Beach, county of Los Angeles, and State of California, have invented a new, original, and ornamental Design for a Therapeutic Light Standard, of which the following is a specification, reference being had to the accompanying drawing, forming part thereof, in which:

Figure 1 is a side elevation of a therapeu-

tic light standard embodying my invention; and

Fig. 2 is a front view thereof.

The dominant feature of the design is the configuration of the standard, its handle and the reflector.

I claim:

The ornamental design for a therapeutic light standard substantially as shown and described.

WILLIS O. PROUTY.
